US00D523310S

(12) **United States Design Patent** (10) **Patent No.:** **US D523,310 S**
Wikle et al. (45) **Date of Patent:** **** Jun. 20, 2006**

(54) **RECIPROCATING SAW**

(75) Inventors: **David L. Wikle**, York, PA (US);
Joseph D. Anderson, York, PA (US);
Jonathan D. Bigden, Baltimore, MD (US)

(73) Assignee: **Black & Decker Inc.**, Newark, DE (US)

(**) Term: **14 Years**

(21) Appl. No.: **29/203,848**

(22) Filed: **Apr. 20, 2004**

(51) **LOC (8) Cl.** **08-03**

(52) **U.S. Cl.** **D8/64**

(58) **Field of Classification Search** D8/69, D8/68, 67, 66, 65, 64, 62, 61; 30/92, 394, 30/393, 392, 377, 376, 371; 74/50, 49; 173/217, 173/216; 83/699.21; 446/145

(57) **CLAIM**

The ornamental design for a reciprocating saw, as shown and described.

DESCRIPTION

FIG. 1 is a perspective view of a reciprocating saw showing our new design.

FIG. 2 is a front view thereof.

FIG. 3 is a rear view thereof.

FIG. 4 is a right side view thereof.

FIG. 5 is a left side view thereof.

FIG. 6 is a top view thereof; and,

FIG. 7 is a bottom view thereof.

The broken lines and the areas within the broken lines form no part of the claimed ornamental design.
